TREE-TYPE DISPLAY RACK

Harry C. Robinson and Thomas F. Challis,
Chattanooga, Tenn., assignors to American
Manufacturing Company, Chattanooga, Tenn.

Original application January 7, 1941, Serial No.
373,500. Divided and this application April 8,
1943, Serial No. 482,306

8 Claims.

(Cl. 211—71)

The present application is a division of our copending application Serial No. 373,500, filed January 7, 1941, which has matured into Patent No. 2,361,060 on Oct. 24, 1944.

This invention relates to a stand or rack for supporting and displaying merchandise, as for example bottled beverages and like commodities, and an object of the same is to provide a knock-down tree-type display stand or rack made up of units which in the main may be readily manufactured from wire or rod stock and which at the same time ensure a firm and stable support for the merchandise.

More specifically, the invention contemplates a tree-type display stand or rack embodying a plurality of shelves or trays assembled in knock-down relation to a central supporting column and a base member, the shelves and base member being made up principally of wire rod members bent into suitable shape and connected by welding, the entire rack being capable of manufacture at a relatively low cost and at the same time being unusually strong and rugged.

The foregoing and other objects and advantages will become apparent in view of the following description taken in conjunction with the drawing, wherein:

Fig. 1 is a view in perspective elevation of a rack constructed in accordance with the invention;

Fig. 2 is a sectional plan view of one of the shelves or trays taken substantially on the line 2—2, Fig. 3; and

Fig. 3 is a view in elevation of Fig. 2.

One purpose for which the improved stand or rack has been devised is for supporting and displaying bottled beverages in cartons, and it has been so illustrated in Fig. 1. The rack consists essentially of a base, a central post and a plurality of shelves or trays which may be packed and shipped in knock-down relation and easily set up at the store or other place where the rack is to be used. The base member and shelves or trays are made up principally of wire rod stock while the central post or column consists of a length of pipe socketed into the base with the shelves detachably mounted in vertical spaced relation thereon.

First generally describing the base and which is claimed in our original application above noted, this comprises legs 10, 10' and 11, 11'. The legs 10, 10' and 11, 11' constitute pairs with each pair made from a single length of wire or rod stock having an elongated rectangular shape in plan view with a flat or horizontal top portion

from which point the wires are bent at an angle or incline downwardly with the lower closed ends of the rectangles forming feet and the free ends of the wires or rods brought back to the flat base and overlapped and welded, forming a rectangular socket. One free end of each one of the rectangular rods or wires which go to make up the legs and feet of the base is bent downwardly to provide clamping prongs 15 and 16 for a purpose which will be presently described.

To reinforce the base, individual lengths or pairs of wires 18 and 19 are positioned with their opposite free ends on the inside of and welded to the lower closed ends of the legs 10, 10' and 11, 11'.

A central column 22 is provided and is made up of a length of pipe with the lower end inserted through the socket provided by the overlapped free ends of the wires which constitute the legs 10—11'. To ensure against looseness of the pipe relative to the base, the prongs 15 and 16 are provided and arranged to be bent inwardly and frictionally engage the pipe under tension and preferably at one side of the latter. This gives in effect a three-point contact. This feature is of advantage particularly in view of the fact that commercial pipe does not run uniform in size or wall thickness, so that if there would be no adjustment of the socket opening, the connection would be loose and rickety and, in fact, it would be difficult to have a uniform fit in the initial assembling operation.

The individual trays or shelves to which the present application is primarily directed are best shown in Figs. 2 and 3 and are indicated at 23, 23' and 24, 24'. The tray or shelf portion 23, 23' is made up of a single piece of wire bent in substantially rectangular form and reinforced by cross rods 25, while the shelf portion 24, 24' is also made up of a single piece of wire bent in the form of a rectangle and reinforced by cross rods 26. The opposite ends of each shelf portion are preferably bent upwardly, as at 27, note particularly Figs. 1 and 3, to provide retaining means for the cartons or other packages which may be disposed on the shelves. The rectangular wire which makes up the shelf portion 24, 24' overlies the wire of the shelf portion 23, 23' and is welded thereto as indicated at 28.

To support the wire framework which makes up the shelves and to also provide a means for securing the shelves to the central post or pipe 22, angle brackets 30 and 31 are provided, each preferably consisting of a strip of metal of generally U-shaped form with the brackets arranged

back to back and welded to one another in the regions indicated at 32. At the central portion of the substantially H-shaped member formed by the brackets 30 and 31, the strips are bent reversely to provide a socket opening 33 but leaving a space 34 in the region of the opening. To secure the brackets to the pipe 22, the latter is formed with a transverse hole and a screw 35 is projected through the strips at the point where they are bent outwardly to form the socket 33, the screw 35 being provided with a wing nut 36.

Due to the fact that the brackets 30 and 31 are welded together at the point 32, when the nut 36 is tightened down, the metal which defines the socket 33 is caused to grip the pipe under tension, thereby holding the shelf or tray unit tightly to the central post or pipe 22. If these strips were not welded together, the clamping pressure exerted by the nut 36 and bolt 35 would bend the socket to the contour of the pipe, which would result in a loose or rickety fit. This spring-clamping effect is enhanced by the top frame being welded at right angles to the bottom frame at the points indicated at 28 and also to the bracket strips at 37 and 38, note Figs. 2 and 3, the wire being bent downwardly at the weld 38 to avoid throwing the top tray out of alignment. This arrangement of the brackets and wire frames also provides maximum supporting capacity with a minimum number of wires.

To assemble the parts of the rack, the pipe 22 is simply socketed into the base, it being understood that the downwardly projecting clamping prongs 15 and 16 are first bent inwardly sufficiently to engage the pipe under tension. This results in a firm and rigid connection between the upright post 22 and wire base. The trays or shelves are then mounted on the post 22 and the wing nuts 36 tightened to hold the shelves rigidly to the post.

The upper end of the post 22 is split or formed with a notch 39 to receive a sign 40.

To knock down or disassemble the rack, it is only necessary to unscrew the wing nuts 36 and remove the shelves or trays and then pull upwardly on the post 22 to remove it from its base.

The rack may be shipped in a compact bundle with the shelves nested, and may be easily and quickly set up at the point of use; it is strong and durable and is capable of supporting a heavy load without danger of sagging or becoming overbalanced.

It will be understood that no attempt has been made herein to enumerate all the advantages of the improved rack, and further, that certain changes in construction and design may be adopted without departing from the spirit or scope of the invention as defined by the appended claims.

What is claimed is:

1. A tree-type display stand including a base, a central post or column projecting upwardly from said base, and one or more trays or shelves secured to said post; each of said trays or shelves comprising a pair of substantially rectangular shaped wire or rod members arranged at right angles to one another having cross-rods and welded together, and means secured to said rectangular tray members formed to provide a central socket adapted to removably engage said post.

2. A tree-type stand for supporting and displaying merchandise and the like including a base, a central post or column projecting up-

wardly from said base, and one or more trays or shelves secured to said post; each of said trays or shelves comprising individual lengths of wire or rod stock shaped in the form of a rectangle and arranged in superimposed relation at right angles to one another and welded together, the outer ends of said rectangular members being bent upwardly to provide retainers and guards for articles disposed on the trays, cross rods secured to said rectangular members adjacent to said upwardly bent ends, and U-shaped elements having the webs of the U adjacent each other and welded together and formed with a central socket for engaging said central column, the arms of the U being welded to one of the frames.

3. A tree-type stand for supporting and displaying merchandise and the like including a base, a post or column projecting upwardly from said base, and one or more trays or shelves connected to said column; each of said trays or shelves comprising wire members and cross-rods forming the tray proper and a bracket comprising a pair of substantially U shaped members having their ends connected to the wire members with their webs extending toward each other to provide a central socket opening, the webs of the U-shaped bracket outwardly from said socket opening being formed with a gradual converging space and being secured together beyond said space.

4. A tree type stand for supporting and displaying merchandise and the like comprising a base, a central post or column extending upwardly from said base, and a tray or shelf supported by said central post, said tray or shelf being composed principally of wire rod members united to provide a unitary assembly, the arrangement of said wire rod members providing crossed frame portions, each frame portion composed of spaced side members and connecting cross rods, certain of the members defining a supporting connection with said central post or column and being formed with substantially parallel portions with oppositely disposed portions at the ends of said substantially parallel portions.

5. A tree type stand for supporting, and displaying merchandise and the like comprising a base, a central post or column extending upwardly from said base, and a tray or shelf supported by said central post, said tray or shelf being composed of rectangular shaped wire frame members united to provide a unitary assembly, the arrangement of said wire frame members providing crossed frame portions, each frame portion composed of spaced side members and connecting cross rods, and means secured to said tray or shelf formed to provide a central socket to support the tray on said central post or column.

6. A supporting tray or shelf for vertical adjustable attachment on an upright post or column comprising rectangular frame portions of wire or rod stock disposed in transverse relation, each frame portion comprising spaced side rods and cross rods and article supporting end portions, said frame portions being fastened together and providing a shelf assembly, and means secured to said tray or shelf formed to provide a central socket adapted to support the tray or shelf on a post or column.

7. A tree-type stand for supporting and displaying merchandise and the like including a base, a central post or column projecting upwardly from said base and one or more trays or shelves secured to said post; each of said trays

or shelves including crossing rectangular wire frame members having cross-wires forming the tray proper, and brackets providing a support member for the tray, said brackets including substantially parallel strips of metal disposed edgewise vertically with intermediate oppositely bent portions providing a socket opening, the strips being welded together outwardly from said socket opening leaving a gradually converging space between the socket opening and the weld, means for clamping the socket formed by said strips to the post, and the portions of said strips beyond said welded connections being bent laterally from each other and having their ends welded to the wire frame members of the tray.

8. A tree-type stand for supporting and displaying merchandise and the like including a base, a central post or column projecting upwardly from the base and one or more trays or shelves connected to said post; each of said trays or shelves comprising crossing rectangular

wire frame members having cross-wires forming the tray proper, and a supporting bracket connected to said wire members, said supporting bracket including a pair of opposed U-shaped metal strips, having the web of the U arranged in substantially parallel edgewise relation and welded to one of the rectangular wire frame members and formed with intermediate oppositely bent portions providing a central socket opening, the ends of the U-shaped metal strips being welded to the other rectangular wire frame members, said strips being welded together outwardly from said socket opening leaving a gradually converging space between the opening and the weld, whereby when the socket is applied over the post and the strips clamped to the post, the metal around the socket opening engages the post under tension.
